(57) CLAIM

The ornamental design for an earmuff, as shown and described.

DESCRIPTION

FIG. 1 is a front perspective view of an earmuff, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, shown in an open configuration;

FIG. 10 is a perspective view thereof, shown in a folded configuration;

FIG. 11 is an enlarged portion view taken from encircled portion labeled, "11," in FIG. 1; and,

FIG. 12 is an enlarged portion view taken from encircled portion labeled, "12," in FIG. 7.

The dot, dot, dash broken lines encircling the enlarged portion views of FIGS. 11 and 12 shown in FIGS. 1,7,11 and 12 illustrate the bounds of the enlarged views of FIGS. 11 and 12 and form no part of the claimed design.

1 Claim, 12 Drawing Sheets
